UNITED STATES PATENT OFFICE.

CHARLES W. WARNOFF, OF ST. LOUIS, MISSOURI.

WIRE SCREEN.

1,157,349.

Specification of Letters Patent.

Patented Oct. 19, 1915.

Application filed January 25, 1915. Serial No. 4,236.

To all whom it may concern:

Be it known that I, CHARLES W. WARNOFF, a citizen of the United States, residing at St. Louis, Missouri, have invented a certain new and useful Improvement in Wire Screens, of which the following is a full, clear, and exact description, such as will enable others skilled in the art to which it applies to make and use the same.

10 This invention relates to wire screens such as are used on the door and window openings of buildings to exclude flies and other insects.

15 The main object of my invention is to provide a window screen that is mounted and retained in operative position in the window frame in a novel manner; that reduces the cost of manufacturing and installing the screen; that enables the screen 20 to be removed from the window frame or arranged in operative position quickly and easily and which overcomes many objectionable features of the adjustable window screens now in general use.

25 Another object of my invention is to provide a wooden frame wire screen in which the wire or screen cloth is covered where it is attached to the frame by removable original portions of the members that constitute 30 the frame.

35 Other objects and desirable features of my invention will be hereinafter pointed out.

Figure 1 of the drawings is a front elevational view of a window equipped with 40 a wire screen constructed in accordance with my invention. Fig. 2 is an enlarged detail sectional view taken on the line 2—2 of Fig. 1. Fig. 3 is a vertical sectional view of the window shown in Fig. 1, illustrating 45 the method of removing the screen from the window frame. Fig. 4 is a vertical sectional view of a window equipped with a full length screen embodying my invention. Fig. 5 is a perspective view of one of the retaining 50 devices on the window frame that hold the screen in position. Fig. 6 is a detail sectional view taken on the line 6—6 of Fig. 2; and Fig. 7 is a perspective view of a piece of the molding from which my improved 55 screen is formed.

Referring to the drawings which illustrate the preferred form of my invention, A designates the frame of my improved screen which comprises two side members and a 60 top and bottom member that are connected together in any suitable manner, said mem-

bers either being mitered at the corners of the screen, as shown in Fig. 1, or butted together in a well known manner. The screen is arranged in the frame B of the 60 window either on the outside of the window sash or on the inside of the window sash, the screen herein shown being arranged on the outside of the sash. In fitting the screen to the window frame I prefer to make the 65 frame A of the screen narrow enough so that comparatively wide joints α will be formed between the side members of the frame A and the adjacent side members of the window frame B so as to eliminate the 70 possibility of the screen sticking in the window frame in case the window frame or the frame of the screen, which are formed of wood, swell or expand. The screen is retained in operative position in the window 75 frame by means of stop strips 1 on the window frame that fit in rabbets or notches formed in the side members of the screen frame A at the inner side of said frame and co-operating retaining devices 2 on the window 80 frame B that project laterally therefrom and lap over or bear against the front faces of the side members of the screen frame A, as shown clearly in Figs. 1 and 2, it being preferably to employ four retaining 85 devices to hold the screen in position, one pair of said devices being arranged adjacent the top of the screen and the other pair being arranged adjacent the bottom of the screen. The stop strips 1 not only act as 90 stops or abutments, which prevent the screen from moving inwardly with relation to the window frame, but they also act as closures for the wide joints α at the sides of the screen frame to prevent flies and other insects from passing through said joints. To remove the screen it is only necessary to raise the frame A high enough so that the lower edge of same will clear the bottom retaining devices 2, then swing the frame A 95 outwardly and move it downwardly so as to withdraw the upper edge portion of same from engagement with the upper pair of retaining devices 2. To mount the screen in operative position these operations are 100 reverse,—the upper edge portion of the screen being slipped under the upper pair of retaining devices 2 and moved upwardly high enough to enable the lower edge portion of the screen to be drawn inwardly over the 110 bottom pair of retaining devices 2.

No hooks or similar fastening devices are

employed to hold the screen in operative position in the window frame, and as the screen of the frame is fitted loosely to the window frame, or, in other words, wide joints are 5 left between the coöperating side members of said frames, there is no liability of the screen becoming stuck or jammed in the window frame, due to swelling of the frame of the screen or the frame of the window. 10 Consequently, my improved screen can be removed and arranged in operative position more quickly and more easily than is possible with the window screens now in general use which are either retained in position by 15 means of hooks or by means of vertically-disposed guide rails or ribs on the window frame that project into grooves formed in the side edges of the frame of the screen, such screens being usually fitted so snugly in 20 the window frame, in order to produce tight joints between the coöperating side members of same, that any swelling or expansion of the window frame or the frame of the screen causes the screen to stick or bind so tightly 25 that the screen is frequently marred or damaged during the operation of removing it or arranging it in position in the window frame.

In addition to the desired features above 30 mentioned, my improved screen can be installed quickly and easily, as the means which retains it in position consists of two simple stop strips 1 that can be tacked to the window frame B quickly and four simple 35 clips or retaining devices 2 that can be tacked to the window frame by a person having no skill in carpentry or screen fitting.

In a full length screen or a screen that extends from the top to the bottom of the 40 window frame B a top cross stop strip 1^a is provided at the upper portion of the window frame so that the inner side of the top member of the screen frame A will bear against same, as shown in Fig. 4, the frame A of the 45 screen being enough shorter than the window frame B to permit the screen to be raised slightly so that the lower edge portion of same will clear the bottom pair of retaining devices 2 during the operation of removing 50 the screen or arranging it in position in the window frame. If desired, a full length screen could be provided at its lower edge with adjustable locking devices 3 that co-operate with the window frame instead of 55 employing a pair of stationary retaining devices 2 on the window frame to prevent the lower edge portion of the screen from swinging outwardly.

The locking devices 3 illustrated in Fig 60 4 each consist of a plunger whose lower end portion enters a hole 3^a in the sill of the window frame when the plunger is moved downwardly after the screen has been properly positioned. At the upper end of said 65 plunger is a bent finger piece 3^b which the

operator can grasp to disengage the plunger from the sill and to swing the lower edge portion of the screen outwardly. Such a locking device can be formed conveniently from a piece of stiff wire and can be connected to the lower cross member of the frame of the screen by means of staples 4, as shown in Fig. 4, the plunger B being preferably provided at a point intermediate the staples or guides 4 with a curved portion 70 3^b which acts as a stop that strikes against the upper staple 4, and thus limits the upward movement of the plunger. Normally, the hook or finger piece 3^b at the upper end of the plunger 3 extends parallel with the bottom cross member of the frame of the screen, but when it is desired to release the screen said hook or finger piece is moved upwardly and given a quarter turn, as shown in 75 Fig. 4, so that it will occupy a convenient 80 position for swinging the lower edge portion of the screen outwardly.

The retaining devices 2 may be formed in various ways without departing from the spirit of my invention, but I prefer to form 90 said devices from sheet metal and provide each device with a base portion for receiving the fastening devices that retain it in position, and a screen-engaging portion 2^a which is preferably curved or half round in 95 cross section so as to impart sufficient strength and stiffness to same and also obtain a curved bearing surface that contacts with the front face of the frame of the screen. When the screen is being removed or arranged in operative position the upper portion of the screen fulcrums or rocks upon the curved portions 2^a of the top pair of retaining devices 2 and when the screen is being arranged in operative position the 100 bottom pair of retaining devices tend to guide the lower portion of the screen inwardly 105 into proper position.

As previously stated, one feature of my 110 present invention consists in a screen in which the wire or screen cloth is covered where it is attached to the frame by removable original portions of the members that constitute said frame. In the wooden 115 frame screens now in use the frame is provided with a rabbet or groove in which the wire is clamped by retaining strips formed from thin strips of wood or pieces of molding that are separate and distinct and which are formed independently of the members that constitute the frame of the screen. In manufacturing the frame the material that is removed from the frame members to form the groove or rabbet is wasted, and when 120 the frame is being put together a separate operation is required to join or fit the ends of the pieces of molding or strips that secure the wire or screen cloth to the frame, thus adding considerable to the cost of 130

manufacturing the screen. In my improved screen the edge portions of the wire or screen cloth is covered by removable original portions of the members that constitute the frame of the screen. In other words, the frame of my screen is formed from members, each of which has a detachable portion 5 that remains attached to the part that carries same during the operation of joining said members together to form the frame and until the wire is arranged in the frame. In manufacturing the members from which the screen of the frame is formed a strip of wood is run through a suitable machine that molds the top face of the portion 5 of the strip and forms a groove 5^a in the strip. At the same operation a slot 5^b is formed in one edge of the strip parallel to the top and bottom faces of same and at right angles to the groove 5^a, but not intersecting same, so as to form a portion 5 that can be easily broken away from the strip, owing to the fact that it is joined to same at only one point, namely, at the inner end of the slot 5^b and the bottom of the groove 5^a, as shown in Fig. 7.

The frame A of the screen is formed from pieces or strips of molding of this character, or, in other words, of the construction shown in Fig. 7, and after the members constituting said frame have been fitted and joined together, the portion 5 of each member is broken off, thus leaving a rabbet at the inner edge of the frame for receiving the screen cloth. After the screen cloth has been stretched and secured in the rabbet of the frame A the removable original portions 5 of the frame are placed over the screen cloth and arranged in said rabbet so as to hide the edge portions of the screen cloth and impart a finished appearance to the screen, the removable portions 5 being retained in position by means of brads or in any other suitable manner. By forming the frame of the screen from four pieces of material instead of eight pieces of material, as has heretofore been the general practice, I materially reduce the cost of manufacturing the screen and I also save a great deal of time and labor in building the screen, owing to the fact that only four members instead of eight members have to be fitted or joined together, it, of course, being understood that the removable portions 5 of the members constituting the frame of the screen are not detached or broken off until after said frame members have been joined together. While I have illustrated this feature of my invention in connection with a

window screen that is held in a window frame in a novel manner, I do not wish it to be understood that said feature is limited to a window screen, as a screen door frame and any type of wooden frame screen can be formed in this manner without departing from the spirit of my invention, which, broadly stated, consists in a screen having a wooden frame formed from members that are provided with removable original portions that cover the edge portion of the screen cloth and impart a finished appearance to the frame of the screen.

While the retaining devices 2 previously described are used primarily for holding a screen in operative position in the frame of a window, they can also be used for retaining a storm sash or storm window in the window frame during the winter months after the screen has been removed.

Having thus described my invention, what I claim, and desire to secure by Letters Patent, is:

1. In a window screen, the combination of a window frame provided with vertically-disposed stop strips, a screen frame having rabbets or recesses formed in the inner faces of its side members so as to receive said stop strips, and laterally-projecting retaining devices on the window frame arranged adjacent the top and bottom of the screen that lap over the front face of the screen frame, said devices having plate-like base portions that are securely connected to the window frame and rigid screen-engaging portions that have curved faces.

2. A screen molding consisting of a strip of material having a longitudinal groove or slot formed in one of its faces, and having a longitudinal slot or groove formed in its edge that projects inwardly toward the groove or slot just mentioned but does not intersect same.

3. A screen molding consisting of a strip of material provided with a removable original portion that can be detached so as to provide a rabbet or space for receiving the screen cloth, said removable portion being joined throughout its entire length to the strip.

In testimony whereof I hereunto affix my signature in the presence of two witnesses, this twenty-third day of January, 1915.

CHARLES W. WARNEHOFF.
